(57) **CLAIM**

The ornamental design for an electronic housing, as shown and described.

DESCRIPTION

FIG. 1 is a front perspective view of an electronic housing showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines showing various regions on the front and rear faces and the unshaded regions therein form no part of the claimed design. The broken lines running from top to bottom in FIGS. 1, 4, and 5 form no part of the claimed design. The broken lines and unshaded regions of FIGS. 6 and 7 form no part of the claimed design.

1 Claim, 5 Drawing Sheets
